KRUPP, AKTIENGESELLSCHAFT, 'GRUSONWERK, OF MAGDEBURG-BUCKAU, GER-
MANY.

TUBULAR GRINDING-MILL.

1,130,644.

Specification of Letters Patent.

Patented Mar. 2, 1915.

Application filed January 9, 1914. Serial No. 811,223.

To all whom it may concern:

Be it known that I, REINHOLD STEINBACH, assistant works manager, a subject of the King of Prussia, and resident of Magdeburg-Buckau, German Empire, have invented certain useful Improvements in or Relating to Tubular Grinding-Mills, of which the following is a specification.

This invention relates to compound tubular grinding mills, the chief object being to enable the material to be readily conveyed from one grinding chamber to the other within the interior of the casing or shell of the mill so as to allow of the casing or shell being made imperforate and of smaller circumference and of a simpler form than heretofore.

According to this invention the mill is provided with an imperforate casing or shell and the material under treatment is conveyed from one grinding chamber to the other through a number of passages disposed around the inner surface of the casing or shell and formed in or between the grinding plates of the respective chambers. The said passages are provided with pockets or enlargements which, during the rotation of the mill, are adapted to collect the ground material in the first chamber and subsequently discharge the same into inclined portions of the passages leading to the second grinding chamber of the mill for further treatment. The inlet opening to each of the passages is provided with a sieve or the like which allows of the passage of the fine material into the pocket thereof for conveyance to the next grinding chamber.

In order that the said invention may be clearly understood and readily carried into effect I will proceed to describe the same more fully with reference to the accompanying drawings in which:—

Figure 1 is a longitudinal section of the improved compound mill comprising two chambers. Fig. 2 represents a portion of Fig. 1 drawn to a larger scale for illustrating more clearly than in Fig. 1 the constructional form of the improved device therein shown. Fig. 3 is a cross section on the line A—B of Fig. 2. Fig. 4 is a cross section on the line C D of Fig. 3. Fig. 5 is a longitudinal section and Fig. 6 a cross section illustrating another constructional form of the improved device. Fig. 7 illustrates a detail in section.

The casing or shell *a* of the mill is divided by the partition *b* into two chambers the first or preliminary chamber *c* and the second or fine grinding chamber *d*. Between the various grinding plates *e* of the preliminary chamber which bear against this partition, openings *f* are provided which are covered with sieves *g* and lead to pocket-like collecting chambers *h*. From these pockets *h* passages *k* branch and extend through the partition *b* or if the partition reaches so far as the casing of the mill they pass around it and lead to corresponding passages in the grinding plates *n* of the second chamber *d*. The latter passages open into the inner portion of the chamber *d*; the passages *k* and *m* may either be cut in the under face of the grinding plates *e* and *n* so that the casing or shell *a* forms one wall of each passage, or they may be located in the interior of the grinding plates. In the first case it is preferable to cover those portions of the inner face of the casing or shell which bound the passages, with lining plates *q* Fig. 7 in order to protect the casing or shell from wear. The plates *q* may be fixed to the casing but a preferable arrangement is to secure them to the grinding plates so that the said lining plates constitute one of the walls of each passage, instead of the casing or shell *a*. The lining plates may be inserted loosely in the joints of the grinding plates, in which case they are held solely by the fixing of the grinding plates to the casing or shell of the mill.

In the construction illustrated in Figs. 1 to 4 when the casing *a* rotates, the material in the chamber *c* falls continuously through the openings *f* in the plates *e* which for the time being are located at the bottom in the downward movement, onto the sieves *g*. These sieves retain the coarse material, while the fine material falls through them and collects in the pockets *h* located below. The material remains in the pockets *h* until the upward movement takes place when the said material begins to slide downward, it is then conducted through the passages *k* and *m* into the chamber *d*.

The construction illustrated in Figs. 5 and 6 differs from the construction described above, in that the sieves are arranged in the pockets *h* so as to obtain a larger sieve area. The material falls through slots or openings *o* formed in the grinding plates *e*

of the chamber *c* onto the sieves, the coarse materials remains behind while the fine material falls through and collects beneath the sieves. In the upward movement, the coarse material slides back through passages *p* into the chamber *c* while the fine material passes through the passages *k* and *m* into the chamber *d*.

Having now particularly described and ascertained the nature of my said invention and in what manner the same is to be performed I declare that what I claim is:—

1. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

2. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

3. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

4. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

5. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

6. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

7. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

8. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

9. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance from one chamber to the next in approximately axial direction near the wall of the drum of the material under treatment.

in the body of the grinding plates, the side of the passages adjacent the concave surface of the drum being open; and a liner covering the open side of each passage, said liners being clamped in position between said grinding plates and the concave surface of the drum.

9. A compound grinding mill comprising an imperforate drum having a plurality of 5 partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate the conveyance in approximately axial direction of the material under treatment, 10 said grinding plates also having a pocket for each of said passages situated at the foremost side of the passage during rotation, said pocket collecting material in a preceding chamber prior to discharging it 15 through a passage into a subsequent chamber; a sieve at the entrance of said pocket for segregating the finer from the coarser material, whereby the coarser material will be returned to the interior of a chamber once 20 for every revolution of the drum.

10. A compound grinding mill comprising an imperforate drum having a plurality of partitioned off chambers in alinement the one with the other, grinding plates on either 25 side of a partition, said grinding plates being provided with a plurality of passages from one chamber to the next and situated adjacent the concave surface of the drum, said passages being obliquely directed relative to said concave surface so as to facilitate 30 the conveyance in approximately axial

direction of the material under treatment, said grinding plates also having a pocket for each of said passages situated at the foremost side of the passage during rotation, 45 said pocket collecting material in a preceding chamber prior to discharging it through a passage into a subsequent chamber; each pocket being connected with the interior of a chamber.

11. A compound grinding mill comprising an imperforate drum having a plurality of partitioned off chambers in alinement the one with the other, grinding plates on either side of a partition, said grinding plates being provided with a plurality of passages from one chamber to the next and situated adjacent the concave surface of the drum, said passages being obliquely directed relative to said concave surface so as to facilitate 50 the conveyance in approximately axial direction of the material under treatment, said grinding plates also having a pocket for each of said passages situated at the foremost side of the passage during rotation, 55 said pocket collecting material in a preceding chamber prior to discharging it through a passage into a subsequent chamber; each pocket being connected with the interior of a chamber; and a sieve at the entrance of said 60 pocket for segregating the finer from the coarser material whereby the coarser material will be returned to the interior of a chamber once 65 for every revolution of the drum.

The foregoing specification signed at Magdeburg this 19th day of December, 1914.
